UNITED STATES PATENT OFFICE.

FERDINAND F. UNCKRICH, OF GALION, OHIO, ASSIGNOR TO THE AMERICAN STEEL
GRAVE VAULT CO., OF GALION, OHIO, A CORPORATION OF OHIO.

VAULT-CLOSURE.

1,184,793.

Specification of Letters Patent. Patented May 30, 1916.

Application filed October 29, 1915. Serial No. 58,623.

To all whom it may concern:

Be it known that I, FERDINAND F. UNCKRICH, a citizen of the United States, residing at Galion, in the county of Crawford and 5 State of Ohio, have invented a new and useful Vault-Closure, of which the following is a specification.

This invention has reference to vault closures and is an improvement upon the vault 10 closures disclosed in Letters Patent No. 872,864, granted to me December 3, 1907, and Letters Patent No. 959,406, granted to me May 24, 1910.

The vault closures described in said Letters Patents have to do with a door structure having radially movable lock bolts with a common centralized manipulating means capable of operation in a manner to cause the compression of the closure against ledges 20 at the margins of the opening to produce a hermetic sealing of the door in the mouth of the vault, and such closing and sealing of the vault is performed whether or not it be desirable to render the closure permanent. 25

The object of the present invention is to simplify the lock-bolt manipulating means whereby the number of parts are reduced 30 and the use of springs is in most part eliminated.

In accordance with the present invention the door is arranged exterior to the vault and the lock bolts are mounted on the inner face of the door in a manner to engage a locking ledge about but interior to the mouth of the vault, the lock bolts being capable of sliding movement radially of the door and of rocking movement with respect to the door. At a mid point of the door 40 there is provided a rotatable cam structure connecting the adjacent portions of the lock bolts for the simultaneous actuation of the bolts. The cam structure is mounted on a screw spindle adapted to rotate the cam 45 structure and also to propel it toward and from the corresponding face of the door to rock the lock bolts, the rotation of the cam structure effecting the projection and retraction of the bolts. These movements are 50 caused by the rotation of the lock spindle in one direction, means being provided whereby a partial rotation of the cam member by and with the spindle brings about the projection of the lock bolts and a continued 55 rotation of the spindle in the same direction,

but with the cam member held against rotation, brings about the hermetic sealing of the door by rocking the lock bolts on fulcrum supports.

The invention will be best understood 60 from a consideration of the following detailed description, taken in connection with the accompanying drawings forming part of this specification, with the further understanding that while the drawings show a 65 practical form of the invention, the latter is not confined to any strict conformity with the showing of the drawings, but may be changed and modified so long as such changes and modifications come within the 70 scope of the appended claims.

In the drawings:—Figure 1 is a cross-section of a vault showing the door closed and in elevation, with the door viewed from the interior of the vault and the lock bolts retracted. Fig. 2 is a view similar to Fig. 1 with some parts broken away and other parts omitted and with the lock bolts projected into locking position. Fig. 3 is a section on the line 3—3 of Fig. 1 but drawn on 80 a larger scale. Fig. 4 is a section similar to that of Fig. 3 except that the lock bolts are in the projected position, and the cam structure has been actuated to hermetically seal the door. Fig. 5 is a section on the line 85 5—5 of Fig. 3. Fig. 6 is a view similar to Fig. 5 but showing a different position of the parts. Fig. 7 is a section on the line 7—7 of Fig. 6. Fig. 8 is a perspective view of a latch bolt. Fig. 9 is a perspective view 90 of a fragment of one of the lock bolts, the showing being of that end of the lock bolt engaged by the cam.

Referring to the drawings there is shown a grave vault 1 of a size to receive a burial 95 casket, the grave vault being customarily made of metal of sheet form similar in size and shape to the boxes into which burial caskets are usually placed. The burial vault 1 has a mouth opening at one end surrounded by a frame or flange 2 and normally closed by a door 3 connected by a hinge 4 to the body portion 1 of the vault, so that the door may be moved into position against the ledge 2 to thereby form a closure for the mouth of the vault. 100

Mounted at the central portion of the door and projecting therethrough is a spindle 5 having that end exposed at the exterior of the door squared, as shown at 6, or otherwise 110

appropriately shaped for the application of a manipulating tool, such as a socket wrench or the like. The other end of the spindle 5 is screw threaded, as shown at 7. The spindle adjacent to the squared end 6 is of circular conformation, as shown at 8, fitting a circular passage 9 through the door, so that the spindle may be rotated about its longitudinal axis. On the side of the rounded portion 8 remote from the squared portion 6 of the spindle the latter is formed with a shoulder 10 adapted to bear against the inner face of the door, the spindle being held to the door by a cotter pin 11 or other suitable means engaging the outer face of the door. Between the shoulder 10 and the screw threaded portion 7 of the spindle said spindle is formed with an annular flange 12 having a beveled periphery 13 and at suitable points the beveled periphery is provided with ratchet teeth 14. There is also provided a circular cam structure 15 provided with a central hub 16 having a threaded axial bore for the screw end 7 of the spindle 5, which screw end in the particular showing of the drawings is provided with left hand threads, so that on turning the spindle to the right the tendency is to move the cam structure or cam block 15 away from seating engagement with the flange 12, the latter then entering an annular recess 17 on that face of the cam block 15 toward the door 3. Surrounding the recess 17 is a flange 18 in most part concentric with the center of the cam block, while about the periphery of the cam block is another similar flange 19. Between the flanges 18 and 19 that face of the cam block presented toward the door 3 is in most part recessed, and extending through the recessed portions is a series of slots 20 each having an inner edge 21 in greater part tangential to a circle concentric with the spindle and terminating at the outer end in a curved extension 22. The other or outer edge of each slot has a curved portion 23 in most part concentric with the curvature of the end 22 of the slot and terminating in a part 24 parallel with the tangential portion of the slot. Each slot has its curved end 22 adjacent to the peripheral portion of the cam block or disk 15, while the tangential portion extends to the opposite side of a radius of the block perpendicular to said tangential portion.

The hub part 16 is thickened to extend axially beyond that face of the cam disk or block remote from the door and there has tangential shoulders 25 corresponding to the tangential walls 21 of the slots 20. Each shoulder 25 is in the particular showing of the drawings perpendicular to the neighboring shoulders and each terminates at one end in a cam lobe 26 forming a shoulder 27 where projecting beyond the next shoulder 25 in order. One of the cam lobes 26 is formed

with an extended recess 28 for a purpose to be described.

On the inner face of the door 3 lock bolts 29 are provided. These lock bolts are of skeleton form and generally triangular in outline.

The base portion of each lock bolt is of an extent approximating the corresponding side of the mouth of the vault, it being understood that the vault is usually of approximately square cross-section with the top of the vault slightly crowned. The basic portion of each lock bolt 29 is formed with spaced lugs or fingers 30 adapted to under-ride holding members 31 secured to the door at appropriate points on its inner face near the margins of the door. The tongues 30 are of such length that when the lock bolts are retracted they will be within the area defined by the inner margin of the flange 2 and when projected these tongues engage the inner face of the flange 2. The inner or smaller end of each triangular lock bolt is formed into a cam lobe 32 having a shoulder 33 at one side and on the face of this lobe 33 toward the cam disk 15 it carries a pin 34 of a length to enter a respective one of the cam slots 20. Each lobe 32 is adapted to engage that face of the cam disk 15 remote from the door and is held in engagement therewith by a retaining plate 35 held to the outer face of the hub 16 by screws 36 or in any other appropriate manner. The marginal portion of the disk 15 on that face engaged by the lobes 32 is rounded, as indicated at 37.

When the parts are in the position shown in Figs. 1 and 3 the lock bolts are retracted and are substantially parallel with the inner face of the door. In this condition of the parts the cam disk 15 is at its position of close approach to the door and the flange 12 is seated in the recess 17. One portion of the cam disk 15 on the face adjacent to the door has a thickened part 38 in which is formed a radially elongated recess 39 constituting a seat for a latch bolt 40 shown separately in Fig. 8. This latch bolt may be quite flat throughout the greater portion of its length with one end beveled to form a latch tooth 41 which when entering the recess 17 engages some one of the teeth 14. The other end of the latch bolt has a laterally offset nose 42 which along one edge is beveled, as shown at 43. The recess 39 is continued at the outer end through the disk 15, thereby forming a passageway 44 into which the nose 42 projects in the path of one of the pins 34 when the latter is in the curved end of the respective cam slot 20. The latch bolt is under the normal control of a spring 45 housed in a lateral extension of the recess 39 and both the spring and latch bolt 40 are held in the recess by a cover plate 46. The tendency of the spring 45, one end of which is lodged in a notch

47 in the latch bolt, is to move the toothed end 41 of the latchbolt into engagement with some one of the teeth 14. When, however, a pin 34 engages the beveled edge 43 of the nose 42 the latch bolt is moved against the action of the spring 45 until disengaged from a tooth 14. When the latch bolt is in engagement with a ratchet tooth 14 the spindle 5 is held against rotation, 10 but when the latch bolt is moved out of engagement with the ratchet tooth 14 the spindle 5 may be rotated. If the threaded end 7 of the spindle be screwed into the cam disk 15 until the flange 12 engages the 15 disk, then any movement of the spindle in a direction to screw the spindle further into the disk only results in turning the disk with the spindle. Any turning movement of the spindle in the opposite direction is 20 prevented by the latch bolt 40 then engaging some one of the teeth 14 by its toothed end 41.

When the lock bolts 29 are in the retracted position the door 3 may be freely 25 opened, the casket may be introduced into the vault and the door again closed. Now, by the application of a suitable tool to the square end 6 of the spindle 5 and turning the spindle in the proper direction, which 30 may be a clockwise direction, the tendency of the screw threaded end of the spindle is to unscrew from the disk, which would result in moving the disk away from the inner 35 face of the door. Movement of the spindle independently of the disk is however prevented by the latch bolt 40, which at this time has its end 41 in engagement with a tooth 14, so that the disk is constrained to rotate with the spindle. The rotative movement of the disk with the spindle continues 40 until the pins 34, which in the retracted position of the lock bolts are in the tangential portions of the slots 20, reach the outer curved portions thereof, this movement resulting 45 in the projection of the lock bolts into engagement with the flange 2. As soon as the pin 34 in that slot 20 connecting with the passage 44 reaches the beveled edge 43 of the nose 42, the latch is withdrawn from 50 the tooth 14 with which it was in engagement, thus disconnecting the disk 15 from the spindle 5. Now the spindle is free to continue its rotation without carrying the cam disk 15 with it and under these circumstances 55 the screw-threaded end 7 of the spindle tends to unscrew from the disk 15, thus propelling the latter along the spindle away from the inner face of the door 3. This causes a similar movement of the inner 60 ends of the lock bolts from the inner face of the door 3, but as the outer ends of these bolts are held by the pins 31, the lock bolts fulcrum on the pins, so that the outer ends of the fingers 30 bear against 65 the inner face of the flange 2 and cause the movement of the door 3 into firm engagement with the outer face of the flange 2. By introducing a packing gasket 47^a between the door and the flange 2 the door may be hermetically sealed where seated 70 against the flange. The pressure of the lock bolts against the cam disk is transmitted through the spindle in a direction to press the shoulder 10 in firm engagement with the inner face of the door, thus providing 75 a seal about the passage 9. The door is thus hermetically sealed and the locking and sealing is performed by a continuous movement of the manipulating tool in one direction. 80

If for any reason it should be desired to gain access to the interior of the vault, this may be done by turning the spindle in the opposite direction to that first described, whereupon a reversal of the operations takes 85 place and the door is finally unlocked.

If it be desired to make the door burglar proof, in which case the closure is permanent, the notch or recess 28 may be utilized. All that is necessary is to provide a latch bolt which may be spring-actuated to move 90 into the recess when the cam member or disk is turned so as to project the bolts, and in such case the cam disk is locked against return rotation under any circumstances 95 short of the application of destructive forces. When the cam disk is locked against rotation in either direction after having projected the lock bolts the door cannot be opened even though the sealing pressure be 100 relieved.

What is claimed is:—

1. A vault closure, comprising a door adapted to seat against the door frame, lock bolts carried by the door, an actuating member for the lock bolts having cams for engaging the lock bolts to project them and also provided with cam slots, the lock bolts having means entering the cam slots for the retraction of the lock bolts by the cam slots, 105 an accessible manipulating means for the actuating member, and means responsive to movements of the lock bolts to couple the manipulating and actuating members for simultaneous movement to project the lock bolts and for then uncoupling them to permit actuation of the actuating member in a direction to clamp the lock bolts. 110

2. A vault closure comprising a door adapted to seat against the door frame, lock bolts carried by the door, an actuating member for the lock bolts having a movement to project the bolts and a different movement to clamp the bolts against the frame, accessible manipulating means for the actuating member, and means responsive to movements of the lock bolts to couple the manipulating and actuating members for simultaneous movement to project the lock bolts 120 and for uncoupling them to permit actua- 125 130

tion of the actuating member in the second-named direction to clamp the lock bolts, said last-named means comprising a radially movable latch bolt carried by the actuating member, and means on one of the lock bolts for engaging the latch bolt to move it radially at the termination of the projecting movement of the lock bolt.

3. A vault closure comprising a door 10 adapted to seat against the door frame, radially movable lock bolts carried by the door, a rotatable actuating member for the lock bolts having a movement to project said bolts and a different movement to 15 clamp the bolts against the frame, accessible manipulating means for the actuating member, and a radially movable latch bolt carried by the actuating member for coupling the manipulating member and the actuating member together, said latch bolt having a 20 beveled offset portion and one of the lock bolts having a pin movable on the projection of the lock bolt into engagement with the beveled portion to move the latch bolt 25 radially to the unlatched position.

4. A vault closure comprising a door adapted to seat against the door frame, lock bolts carried by the door, a rotatable and 30 axially movable cam member adapted to engage the inner ends of the lock bolts to project said lock bolts, and also provided with cam slots, the bolts having pins entering the cam slots, a screw spindle extending through the door and engaging the cam member to move it axially, and a radially 35 movable latch mounted on the cam member with the latch and spindle having coacting portions for coupling the spindle and cam member together, and said latch being located in the path of the pin on one of the 40 lock bolts with said portion of the latch coactively related to the pin for movement of the latch out of engaging relation with the spindle when the lock bolt is in the projected position.

5. A vault closure comprising a door adapted to seat against a door frame, lock bolts carried by the door, a rotatable and 50 axially movable cam member having cam slots with the bolts provided with means for entering the slots and the cam member also being provided with cam portions for engaging the lock bolts to project them, a screw spindle extending through the door 55 and engaging the cam member to move it axially, and latch means carried by the cam member with said latch means and the

spindle having coacting portions for coupling the spindle and cam member together, and said latch means and one of the lock 60 bolts having coacting parts for the movement of the latch means out of engaging relation to the spindle when the lock bolt is in the projected position.

6. A vault closure, comprising a door 65 adapted to seat against a door frame, lock bolts carried by the door, a rotatable cam member having cam slots and cam shoulders with the lock bolts having parts entering the cam slots and other parts engaged by 70 the cam shoulders, a screw spindle extending through the cam member for moving said cam member axially by rotative movements of the spindle to cause clamping of the lock bolts against the door frame, and 75 a latch carried by the cam member for coupling the spindle and member to cause rotative movements of the member with the spindle, said latch and one of the lock bolts having coacting portions for causing the 80 uncoupling of the spindle and cam member when the lock bolt is in the projected position.

7. A vault closure, comprising a door 85 adapted to seat against a door frame, lock bolts carried by the door, a rotatable and axially movable cam member having cam slots and cam shoulders, with the lock bolts provided with projecting portions entering the cam slots and shoulders engaged by the 90 cam shoulders of the cam member for the positive projection and retraction of the lock bolts, a latch bolt carried by the cam member with a nose in the path of a projection of one of the lock bolts to be retracted by said lock bolt when the latter is in the projected position, and a manipulating member extending through the door into 95 accessible position and provided with a threaded portion threaded through the cam 100 member to cause axial movements of the latter by rotative movements of the spindle, said spindle being also provided with a ratchet member in the path of the latch for coupling the spindle and cam member together.

In testimony that I claim the foregoing as my own, I have hereto affixed my signature in the presence of two witnesses.

FERDINAND F. UNCKRICH.
